UNITED STATES PATENT OFFICE.

ANTON OLSEN FÖRISDAL, OF LILLEHAMMER, NORWAY.

BRUSH OR BROOM HOLDER.

Application filed June 30, 1921. Serial No. 481,701.

(GRANTED UNDER THE PROVISIONS OF THE ACT OF MARCH 3, 1921, 41 STAT. L., 1313.)

To all whom it may concern:

Be it known that I, ANTON OLSEN FÖRISDAL, a subject of the King of Norway, residing at Lillehammer, Norway, have invented
 5 certain new and useful Improvements in Brush or Broom Holders (for which I filed application in Norway March 6th, 1917, Patent No. 29,541; in Denmark March 26th, 1919, Patent No. 27,048; in England May 10 25th, 1918, Patent No. 119,424; in Sweden January 31st, 1919, Patent No. 45,710); and I do hereby declare the following to be a full, clear, and exact description of the invention, such as will enable others skilled 15 in the art to which it appertains to make and use the same, reference being had to the accompanying drawings, and to letters or figures of reference marked thereon, which form a part of this specification.

20 My invention relates to means for locking or clamping the heads of brooms, brushes and the like to a handle or stick.

An embodiment of my invention is shown in the accompanying drawing, Fig. 1 being 25 a side view and Fig. 2 a rear view of the same.

The locking means comprises two separate locking members 1 and 2, which may suitably be stamped from sheet iron. The 30 member 1 is provided with two teeth or points 3 which are driven into the back of the stick 4. Said member is provided in front with a central curved hook 5, adapted to grip the edge of the back plate 7 of the 35 broom or brush to be attached to the handle. At either side of the central hook 5 the locking member 1 is provided with a shoulder 6 being spaced so far from said hook 5 as to ensure sufficient support in a 40 transverse direction.

The other locking member 2 is a completely loose part which is clamped against the broom handle or stick by means of a screw bolt 8 passing through the locking 45 member 1 and the handle, a nut 9 on said screw bolt serving to press the member

against the handle, enclosing it with its upper curved portion 10. On tightening up the nut 9 the lower hook 11 on the member 2 will move in an arc having the portion 10 50 for its fulcrum. As will be seen, the hook 11 will press against the edge of the back plate 7 and at the same time swing the same upwards so as to press its upper face firmly against the shoulder 6. In this way 55 a very secure locking of the brush head to the handle or stick is effected and at the same time the members 1 and 2 will be locked firmly to the handle their three points of contact being situated on opposite sides of 60 the handle and properly spaced.

Claims.

1. A brush or broom holder comprising in combination a stick, a stationary jaw attached to the stick and adapted to hook over 65 the front edge of the brush head, spaced shoulders on said stationary jaw adapted to engage the back of the brush, a movable jaw having a concave upper end bearing on the stick and a curved lower end adapted to 70 hook over the rear edge of the brush head and means for causing the movable jaw to swing about its upper end as a fulcrum, thus clamping the brush head between the stationary and movable jaws. 75

2. A brush or broom holder in accordance with claim 1 wherein the shoulders of the stationary jaw supporting the brush head are on either side of the stick and wherein the means for causing the movable jaw to 80 swing comprises a bolt passing through the stick and movable jaw and a nut on said bolt adapted to move the movable jaw.

In testimony that I claim the foregoing as my invention, I have signed 85 my name in presence of two subscribing witnesses.

ANTON OLSEN FÖRISDAL.
